UNITED STATES PATENT OFFICE.

ELMER MILTON WALDREF, OF LEEDS, WISCONSIN.

TOBACCO-LATH HOLDER.

No. 902,784.

Specification of Letters Patent.

Patented Nov. 3, 1908.

Application filed May 25, 1908. Serial No. 434,965.

To all whom it may concern:

Be it known that I, ELMER MILTON WALDREF, a citizen of the United States, residing at Leeds, in the county of Columbia and State of Wisconsin, have invented a new and useful Tobacco-Lath Holder, of which the following is a specification.

My invention relates to a device for holding a tobacco lath when stripping leaves from the stocks and when removing the stocks from the lath; and the object of my invention is to provide a device to hold tobacco lath so that the tobacco stocks can be removed from the lath as soon as the tobacco leaves are stripped from the stocks which obviates the rehandling of the lath to remove the stocks from them. I attain this object by the mechanism illustrated in the accompanying drawing, in which—

Figure 1 is a vertical section of the entire device. Fig. 2 is a sectional view.

Similar letters refer to similar parts throughout the several views.

The tobacco lath holder *a*, fastened to a

support by bolt *b*, holds lath *c* in position 25 while the leaves are stripped from the tobacco stocks. When the stripper pulls the stocks forward in the act of removing them from the lath, the holder *a*, assumes position 30 *d* and produces a friction at *e* and *f*, thus preventing the lath from slipping from the holder *a*, while the stocks are being removed. After the stocks are removed from the lath, the holder goes back to original position. The lath is removed from the holder by raising the lath at point *g* and then pulling towards stripper.

I claim:

A tobacco lath holder comprising a body having an enlarged opening therein to receive the end of a lath, and means for loosely supporting the holder, substantially as described.

ELMER MILTON WALDREF.
